UNITED STATES PATENT OFFICE.

WILLIAM C. EDGE, OF NEWARK, NEW JERSEY.

DESIGN FOR A WATCH-CHAIN.

SPECIFICATION forming part of Design No. 13,661, dated February 27, 1883.

Application filed July 21, 1882. Term of patent 14 years.

To all whom it may concern:

Be it known that I, WILLIAM C. EDGE, of Newark, in the county of Essex and State of New Jersey, have invented a new and original 5 Design for Watch-Chain, of which the following is a specification.

Figure 1 is a photographic face view of my new design for watch-chain; Fig. 2, a photographic face view of a modification thereof; 10 Fig. 3, a cross-section of Fig. 1, and Fig. 4 a cross-section of Fig. 2.

This invention relates to a new form or configuration of watch-chain; and it consists in making the chain cross-shaped in cross-section, 15 so as to produce projecting ribs on its faces.

In the accompanying drawings, the letter A represents my new chain, the same being made up of links, as indicated. On each of the two faces of the chain is a projecting rib, a,

so that in cross-section the chain will be in 20 form of the letter X or of a cross. The length of the ribs may be slightly varying, as will appear by comparing Figs. 3 and 4. The effect of this configuration upon the eye is very pleasant, as the projecting ribs throw a peculiar shadow on the adjoining links.

The chain is applicable, whether used for watch-chains or analogous structures.

I claim—

The design for flexible chain A, having ribs 30 a projecting from its faces, substantially as shown.

This specification of my invention signed by me this 10th day of May, 1882.

WILLIAM C. EDGE.
